UNITED STATES PATENT OFFICE.

WILLIAM W. NELSON, OF BROOKLINE, MASSACHUSETTS.

BANJO.

Application filed March 21, 1927. Serial No. 176,977.

The invention relates to an improvement in banjos or similar stringed instruments.

The object of the invention is to improve the banjo both structurally and in point of tone-giving quality. Especially is it the object of the invention to improve the tonal qualities of the instrument by providing it with a very deep resonator or one that will substantially envelop the body of the instrument.

The invention can best be seen and understood by reference to the drawings, in which—

Figure 1 is a plan of the improved banjo. Fig. 2 is a cross section thereof.

Fig. 3 is a cross section of a portion of the banjo in enlarged detail, and

Fig. 4 is a plan of a portion of the banjo in enlarged detail.

Referring to the drawings:—

1 represents the body of the banjo. 2 is the neck. 3 is a crossbar or brace extending crosswise through the chamber of the body, reinforcing it and assisting also in the retention of the neck.

25 Mounted upon the top edge of the body is a ring 4, preferably a hollow ring, with a series of openings 5 on the interior side thereof. The ring is provided with an upward extension 6 presenting a rounding top edge

30 7 over which is stretched a skin or vellum 8 secured to a skin hoop 9. Bearing against this hoop is a tension hoop 10 which is adapted to draw against the hoop 9 for stretching and retaining the skin or vellum 8. The ten-

35 sion hoop 10 is one preferably angular in cross section having a rim-forming portion 11 around the head of the banjo and a flange-forming portion 12 with bearing against the skin hoop and extension beyond it.

40 The tension hoop 10 is drawn against the skin hoop 9 by means of a number of tension bolts 13. These bolts are passed through the portion 12 of the tension hoop until the heads of the bolts have drawing engagement therewith, while the threaded shanks of the bolts fasten into a horizontal flange-forming portion 14 of a ring 15 which snugly embraces the body of the banjo with bearing against a shoulder 16 thereon. The

50 flange-forming portion 14 of the ring 15 ex-

tends all around the body of the banjo excepting that it is cut away at the point of the neck of the banjo so as not to weaken the neck, the ring 15, however, being continued around the body of the banjo at this point.

17 represents the resonator which fits over the body of the instrument and comprises a back 18 and a turned edge or rim 19. The back is larger than the body of the instrument extending well beyond the same, and the turned edge or rim of the resonator is made very deep, preferably extending to a point just inwardly removed from the head of the banjo. To the flange-forming portion 12 of the tension hoop is fastened a space plate 20 having tonal openings 22 within it. This plate may be made in one piece or in sections, and is fastened to the tension hoop, crossing the space between the tension hoop and the rim of the resonator, and is preferably secured to the rim for supporting the resonator. The inner portion of the plate 20 is attached to the tension hoop by means of the tension bolts 13, the plate being interposed between the heads of these bolts and the portion 12 of the tension ring. The outer portion of the plate extends over the top edge of the rim of the resonator and is attached thereto by fastenings 21.

Having thus fully described my invention, I claim and desire to secure by Letters Patent of the United States:—

In a banjo, the combination comprising the body of the banjo, a vellum head, a skin hoop to which the head is secured, a tension hoop arranged to tighten against the skin hoop for stretching the head, tension bolts passed through the tension hoop, means connected to said body into which the tension bolts fasten by which the tension hoop is drawn against the skin hoop for stretching the head on tightening the tension bolts, a resonator connected to said body having a back with a rim overlapping said body, and a space plate provided with tonal openings fastened to the tension hoop by the tension bolts and bridging the space between the tension hoop and the rim of the resonator.

WILLIAM W. NELSON.
